UNITED STATES PATENT OFFICE.

WILLIAM ARCHIBALD LESLIE HAMMERSLEY, OF LEEK, COUNTY OF STAFFORD, ENGLAND.

MACHINE FOR FULLING, WASHING, SCOURING, CLEANING, AND BEETLING YARNS AND TEXTILE FABRICS.

SPECIFICATION forming part of Letters Patent No. 414,810, dated November 12, 1889.

Application filed June 20, 1889. Serial No. 314,990. (No model.) Patented in England November 5, 1887, No. 15,097.

To all whom it may concern:

Be it known that I, WILLIAM ARCHIBALD LESLIE HAMMERSLEY, a subject of the Queen of Great Britain, and a resident of Leek, in the 5 county of Stafford, England, have invented certain new and useful Improvements in Machinery for Fulling, Washing, Scouring, Cleaning, and Beetling Yarns and Textile Fabrics, (for which I have obtained a patent in Great 10 Britain, No. 15,097, dated November 5, 1887,) of which the following is a specification.

My invention relates to improvements in machines for fulling, washing, beating, and softening yarns and textile fabrics; and the 15 object is to produce a machine or apparatus for fulling, washing, scouring, cleaning, beating, softening, and beetling yarns and textile fabrics, either in the hank or in the piece, and effectually removing all creases and dirt, 20 and at the same time subjecting them to streams of water or other liquids adapted for the purpose. Another object is to prevent any undue strain upon the fabrics during the fulling or beetling operation, and, finally, to thoroughly cleanse or scour the fabrics by water 25 or liquids under pressure.

To this end my invention consists of a rectangular frame, in which a series of beaters receiving a rocking motion are arranged on 30 transverse shafts, operated by gearing in such manner as to strike against stationary buffers secured to the sides of the frame. The buffers are placed at an angle to obviate any undue strain upon the yarn or other fabrics.

35 It also consists in arranging suitable perforated pipes in close proximity to the fabrics, so that water under pressure may be sprayed against them for cleansing purposes; and it consists in the construction of certain 40 details and arrangements of parts, as will be more fully described hereinafter, and specifically pointed out in the claims, reference being had to the accompanying drawings, and to the letters of reference marked thereon.

45 Like letters indicate similar parts in the different figures of the drawings, in which—

Figure 1 represents a side elevation of the machine partly broken away. Fig. 2 is an end elevation of the same. Fig. 3 is a top view 50 or plan of the same.

In the drawings, A represents a suitable

frame of proper size and material and provided with bearings and brackets for the shafts and details. At the ends of said frame are affixed upright brackets and pedestals B 55 for carrying a shaft C, driven by means of a belt and pulley from any suitable motive power, and on said shaft are secured pulleys c^2 , connected by cross-belts with the intermediate shafts for driving the beaters, &c. On 60 the lower rail a of the frame are arranged the rocking shafts D in bearings d . The shafts D carry at their extremities the vertical carriers or arms c , on which the rocking beaters E are affixed, for beating or beetling 65 the hanks of fabric under treatment, and said beaters serve to beat the fabrics, passing over the surface of the permanent or stationary buffers H, arranged at an angle of five degrees. This is of the highest importance, as it ob- 70 viates any undue strain upon the fabrics while being manipulated. For instance, delicate or fine strands of silk fibers would be broken, causing serious loss and expense.

To the rocking shaft D the lever-arms d^2 75 are attached, and moved to and fro by means of a rod f and eccentric F on the intermediate shafts g , revolving in suitable bearings g' . The shafts g , carrying the fly-wheels g^3 , are driven by belts i and tight and loose pulleys 80 i' from the pulleys c^2 on the main driving-shafts C.

The letters g^3 indicate the handles of belt-shifting devices (not shown) of any well-known construction, which may serve to shift 85 the belts i from one pulley to the other, as desired.

On the sides of the frame A and opposite each of the beaters E are affixed the brackets h for supporting the stationary buffers H, 90 placed, as stated above, at an angle of five degrees with a vertical line. The buffers and beaters are made of wood or other suitable materials and of any width to suit the fabrics under treatment, and if necessary they 95 may be covered with sheet-copper or other facing capable of withstanding the expansion and contraction from heat and moisture. Attached to the shafts g is the beveled wheel j' , gearing with the bevel-wheel j^3 on the inclined shaft k , having at its other end the worm k' , meshing with the wheel l' on the

transverse shaft *l*, working in bearings *l*. This shaft overhangs the sides of the frame and carries at each of its extremities a reel *G* of any desired size or width, and consists of a series of wooden or metal bars secured to heads at each end. These reels are designed for carrying the hanks of yarn and keep them continually moving between the two surfaces of the beaters and buffers, as shown by the 10 dotted lines and marked *o*.

To keep the hanks *o* straight or expanded, a loose roller *n* below the reels is placed on a stud *n'*, carried by a bracket *n''* in a slot *p* in the frame sides and made adjustable by a 15 nut and bolt to suit different lengths of hanks. For washing the fabrics so mounted, a pipe with taps and extending the whole length of the frame supplies water or other liquid under pressure, and is provided with branches 20 *r*, Fig. 1, having small perforations and regulated by a three-way cock to vary the jets of water, as desired. In this manner the fabrics are thoroughly impregnated while undergoing the beating process, and thus cleansed of all 25 dirt; or otherwise the requisite liquid is fed to the fabrics.

To protect the fabric and prevent it from getting entangled in the various pedestals, one or more brass rods *s* are attached to the whole 30 length of the frame.

The openings in the frame-sides and the bearings can be protected against wet or dirt in any manner.

Reversing motion for working of the 35 fabrics in opposite directions is obtained by means of a cross-belt working on the main line in the ordinary manner.

Having thus described my invention, what I claim, and desire to secure by Letters Patent, is—

40

1. The combination of a frame having brackets for a main shaft *C* and pulleys with cross-belts for operating transverse shafts *g*, provided with eccentrics moving the rocking beaters against stationary buffers, and the 45 reels for carrying the hanks, as and for the purposes set forth.

2. The stationary buffers having their faces placed at an angle of five degrees and the rocking beaters operated by eccentrics and 50 rods, in combination with a series of reels placed on the ends of transverse shafts and operated by worms and wheels, all arranged as set forth.

3. The combination of rocking beaters and 55 stationary buffers with reels carrying the hanks between said beaters and buffers, and the perforated branch pipes connected to a main water-pipe for conveying water to said hanks, arranged as and for the purpose specified.

4. The frame *A*, carrying a series of rocking beaters *E*, stationary buffers *H*, and reels *G*, for carrying the hanks passing over loose rollers *n*, in combination with the gearing 65 herein described and the perforated branch pipes, all as and for the purposes set forth.

I affix my signature to the foregoing specification.

WILLIAM ARCHIBALD LESLIE HAMMERSLEY.
